RETURN BEND

Henry E. Muchnic, Atchison, Kans., assignor to
 The Locomotive Finished Material Company,
 Atchison, Kans., a corporation of Kansas

Application January 17, 1935, Serial No. 2,189

5 Claims. (Cl. 285—20)

My invention relates to return bends for oil stills and the like and pertains more especially to a sectional return bend of the stream line type involving separable housings in which the ends of the tubes are secured and whereby the return bend section is held in position and maintained in fluid relation with the tube or pipe ends through proper manipulation of regulable means carried by the housings.

10 The invention has for its object the provision of means whereby the separable housings are maintained in proper cooperating relation and at the same time permitted a predetermined degree of independent movement laterally either 15 toward or away from each other, without actual contact between adjacent housings, so as to provide for any slight variations that may occur in the distance between center to center of adjacently arranged pipe or tube sections.

20 The invention provides an adjustable coupling between substantially parallel pipes or tubes which can be made pressure tight regardless of any small variations in the tube centers and in the center to center dimension of the U-bend 25 section.

The invention, more specifically stated, involves a separate housing section for each pipe or tube end, which is also adapted to receive 30 one end of the U-bend section; with the adjacently disposed faces of the housings formed to receive means of predetermined type adapted to cooperate with said housing formations to limit the lateral movement of the housings with their attached pipe ends in conjunction with means 35 whereby improper longitudinal movement of the respective pipes or tubes will be prevented and the housings clamped in their proper positions.

The above enumerated objects and the advantages inherent in the invention will all be 40 more readily comprehended from the following detailed description of the accompanying drawing, wherein:

Figure 1 is a sectional plan view of my invention wherein one of the return bend housings and 45 a portion of the bend proper are in section while the other housing and end of the bend proper are in plan.

Figure 2 is a sectional view taken substantially on the offset line 2—2 of Figure 1 looking 50 in the direction of the arrows.

As heretofore stated, my invention relates more especially to return bends for oil stills wherein the pipes of the stills are arranged in tiers or vertically spaced rows and the ends of adjacent pipes or tubes united by a stream line con-

nection or U-bend adapted to present little or no resistance to the flow of the oil; a construction wherein the bend section may be readily removed to permit access to the interiors of the pipe sections for cleaning or otherwise when occasion requires. The invention in its more specific embodiment as exemplified in the drawing involves the housing sections 10, 10 of corresponding and mating construction and each of suitable thickness as shown in Figure 1 to provide the pipe or tube receiving openings 11 of predetermined internal circumference to permit the tube end to be forced into interlocking relation with the wall of the opening.

The other ends of the openings 11 are preferably shown provided with a flared orifice at 12 adapted to receive the tapered ends 13 of the U-bend section 14.

Each housing section 10 on opposite sides of the openings 11 is provided with parallelly arranged mule ears or projections 15, 15 which are preferably transversely arcuate or conform with the marginal or side wall contour of the housing section; the outwardly projecting mule ears 15, 15 being spaced apart sufficiently to receive an end of the U-bend section 14 therebetween; and the mule ears 15 of each housing section 10 are transversely aligned with the flared orifice 12 of the opening 11.

Each mule ear or projection 15 is provided adjacent its outer end with a suitable opening as at 16 adapted to receive one of the ends of a yoke member 17, as shown at the right in Figures 1 and 2; and the enlarged center portions of these yoke members 17 are provided with tapped openings therethrough to receive the threaded set screws 18.

The U-bend at each end on the outer surface is preferably provided with enlargement or boss 19 having a countersunk seat for the end of the 40 set-screw 18.

In arranging the banks or tiers of pipes or tubes in horizontal and vertical rows and in the casting or fabrication of the U-bends there frequently are small variations in the tube centers 45 and in the center to center dimension of the U-bend ends. In order to compensate for such variations I have provided the two separable housing sections 10, 10, whose opposing faces are each provided with a dove-tail slot 20 extending 50 entirely through the housing section as shown in Figure 1, with the narrow open side of the slot arranged on the outer face or side of the housing section as shown in Figure 2.

The matching slots 20, 20 are then brought 55

into open side to side relation to receive a double dove-tailed key 21 which is inserted endwisely either from the upper or the lower side of the combined housing as viewed in Figure 1. The 5 key member 21 is preferably made of transverse dimensions slightly less than the transverse dimensions of the combined or double dove-tailed slot 20.

This permits the two housing sections to move 10 laterally toward or away from each other a predetermined extent, the double dove-tail key 21 maintaining proper associated relation between the housing sections; at the same time the play or clearance between the walls of the slots in the 15 housing sections and the key 21 is such that the housing sections cannot contact with each other along the median line of the structure. With this relation between the key and the slots, it is apparent that the housing sections with their 20 respective tube ends are capable of a predetermined amount of lateral adjustment adapted to any small degree of variations that may exist in the tube centers and in the center to center dimensions of the ends of the U-bend.

25 The body portion of the double dove-tail key 21 is of length slightly less than the thickness of the housing sections where they are provided with the slots 20, 20; and the opposite ends of the key are each provided with a threaded stud or pin 30 portion 22 which extends beyond the walls of the housing sections. The threaded ends or pin portions 22 are each shown provided with a relatively large washer 23 which is adapted to overlap the adjacent portions of the two housing sections, as shown in Figure 2.

After the washers 23 have been put into place on the ends of the key member 21, a nut 24 is then screwed onto each threaded end or pin; the nuts being screwed lengthwise of the ends 40 or pin portions 22 until they firmly hold the washers 23, 23 in clamping relation with the housing sections.

The washers 23, 23, through the action of the nuts 24, will maintain the proper alignment of the housing sections with each other and at the same time yieldingly clamp the housing sections 45 with their allied tube ends in place.

The matching sides of the housing sections are positioned so that the key member 21 may be 50 endwisely inserted into the matching slots 20, 20; the ends of the key member being provided with the washers 23 and nuts 24; the latter being merely loosely screwed onto the threaded ends or 55 pins of the key member 21 so as to permit lateral adjustment of the housing sections. The return bend section 14 is then put into place by inserting an end between the mule ears of a housing section and adjusting the housing section so that 60 the end of the U-bend section 14 will register with and may be pressed into the beveled seat 12 of the opening 11. After both ends of the return bend 14 are in place on their seats in the housing sections, the pressure applying means, namely 65 the yoke members and set screws, are then put into pressure applying condition, thereby firmly forcing the ends of the U-bend into the beveled orifices and into fluid tight relation with the housing sections. When the elements are 70 aligned and connected as described, the nuts 24 are then screwed up tightly and the washers forced into firm clamping relation with the housing sections.

The exemplification of the invention is believed 75 to be the best embodiment, but modifications are

possible without, however, departing from the spirit of my invention.

What I claim is:—

1. In a return bend structure of the character described, a pair of housing sections, each apertured to receive an end of a U-bend section and the end of a tube, the juxtaposed sides of the sections being each provided with a dove-tailed slot; a double dove-tailed key member endwisely insertable in the matching slots of the housing sections, the cross sectional dimensions of said key being less than the corresponding dimensions of the slots so as to permit a limited degree of independent movement of the housing sections relative to each other in any direction in a plane 15 perpendicular to the tubes; and means for holding the U-bend section in contact with the housing sections.

2. In a return bend structure of the character described, a pair of housing sections, each apertured to receive an end of a U-bend section and the end of a tube, the juxtaposed sides of the housing sections being each provided with a dove-tailed slot; a double dove-tailed key member insertable in the matching slots of adjacent housing 20 sections, the cross sectional dimension of the key member in a direction parallel with the adjacent faces of the housing sections being less than the corresponding dimension of the slots to permit a limited degree of independent movement of the 25 housing sections relative to each other, while the transverse dimension of the key member in a direction toward the tube-centers is greater than the corresponding dimensions of the two slots and a spaced relation between the two housing sections maintained; and means for holding the U-bend section in place.

3. In a return bend structure of the character described, a pair of housing sections, each apertured to receive an end of a U-bend section and the end of a tube; the juxtaposed sides of the sections being each provided with a dove-tailed slot; a double dove-tailed key member endwisely insertable in the matching slots of the housing sections, the cross sectional dimensions of said key being less than the corresponding dimensions of the slots so as to permit a limited degree of independent movement of the housing sections relative to each other in any direction in a plane 40 perpendicular to the tubes; means having adjustable relation with the key member and adapted to effect clamping engagement with the housing sections; and means for holding the U-bend section in contact with the housing sections.

4. In a return bend structure of the character described, a pair of housing sections, each apertured to receive an end of a U-bend section and the end of a tube; the juxtaposed sides of the housing sections being each provided with a dove-tailed slot extending from front to rear; a double dove-tailed key member insertable in the matching slots of adjacent housing sections, the transverse dimension of the key member in a direction parallel with the adjacent faces of the housing sections being less than the corresponding dimensions of the slots to permit a limited degree of independent movement of the housing sections, the ends of the key member being screw-threaded; means adapted to cooperate with the threaded ends of the key member, 60 to effect clamping engagement with the housing sections; and means for holding the U-bend section in place.

5. In a return bend structure of the character described, a pair of housing sections, each aper-

tured to receive an end of a U-bend section and the end of a tube, the housing sections to be arranged in juxtaposed relation, and a dove-tail connection between the adjacent sides of the housing sections wherein the cross-sectional dimensions of the dove-tail element are less than

the corresponding dimensions of the dove-tail groove whereby the housings are permitted a limited movement in any direction in a plane perpendicular to the tubes.

HENRY E. MUCHNIC.
